CLAIM

The ornamental design for a handbag, as shown and described.

DESCRIPTION

FIG. 1 is a front perspective view of a handbag showing my new design;

FIG. 2 is a front view of the handbag shown in FIG. 1 (with the rear view being a mirror image thereof);

FIG. 3 is a right side view of the handbag shown in FIG. 1 (with the left side view being a mirror image thereof);

FIG. 4 is a top view of the handbag shown in FIG. 1; and,

FIG. 5 is a bottom view of the handbag shown in FIG. 1.

The broken line showing of the zippers and zipper pulls is for illustrative purposes only and forms no part of the claimed design.
